UNITED STATES PATENT OFFICE.

ARNOLD WILLIAM MANSBRIDGE AND SIDNEY JOHN NASH, OF WINNIPEG, MANITOBA,
CANADA.

VAPORIZING ATTACHMENT.

1,130,915.

Specification of Letters Patent.

Patented Mar. 9, 1915.

Application filed March 17, 1914. Serial No. 825,288.

To all whom it may concern:

Be it known that we, ARNOLD WILLIAM MANSBRIDGE and SIDNEY JOHN NASH, both of the city of Winnipeg, in the Province of Manitoba, Canada, have invented certain new and useful Improvements in Vaporizing Attachments, of which the following is the specification.

The invention relates to an auxiliary attachment for vaporizing oil and the object of the invention is to provide an inexpensive efficient device which can be attached to an engine carbureter and which will when in use effect an almost instantaneous vaporization of the fuel feed thereby allowing the engine to be started very quickly.

A further object is to provide a device which when applied to a carbureter will make it possible to start an engine burning the cruder oils such as kerosene or coal oil by quickly vaporizing the crude oil in the carbureter and thereby obtaining immediately an effective explosive charge for the cylinder.

With the above objects in view the invention consists essentially in a cup shaped receptacle, a suitably insulated wire coil contained in the receptacle and binding screws connected with the ends of the wire, one being in electrical connection with the receptacle and the other insulated therefrom, the parts being arranged and constructed as hereinafter more particularly described and later pointed out in the appended claims.

Figure 1 represents a side view of the invention as applied on an engine carbureter. Fig. 2 represents an enlarged detailed vertical sectional view through the lower portion of a carbureter with our device applied and appearing in section. Fig. 3 represents a plan view of the attachment.

In the drawing like characters of reference indicate corresponding parts in each figure.

1 represents an engine provided with the usual cylinders 2, inlet manifold 3 and exhaust manifold 4, the inlet manifold being supplied with a carbureter 5 of any approved type which controls the supply of the fuel feed to the engine.

In the present case 6 is the oil supply pipe leading to the carbureter, the supply of oil being controlled as is customary by the float valve 7 operating in the carbureter well 8 and 9 represents the customary needle valve

controlling the orifice 10 through which the oil is drawn into the mixing chamber 11.

It is to be understood that the above parts form no part of our invention being simply described so that the application of the attachment can be clearly understood.

We might here remark that in the colder countries difficulty is experienced in starting an engine with a carbureter of the type shown (without our attachment) even with gasoline owing to the difficulty of obtaining a good firing mixture in the mixing chamber. In instances where the cruder oils such as kerosene or coal oil are used it is impossible to start the engine in cold temperatures and very difficult in warm temperatures.

With our attachment shortly described applied and in use the engine can be started almost instantaneously, even under the usual adverse conditions where one of the cruder oils is used as a fuel.

Referring again to the drawing, 12 represents the attachment which is screw threaded into the carbureter and connected in a suitable electric circuit. It comprises the following parts.

13 is a cup shaped receptacle having the upper end exteriorly screw threaded and screwed into the bottom of the carbureter so that it opens to the well thereof and when applied fills with the oil contained in the well.

14 is an insulating cup-shaped casing fitted within the receptacle and containing a spirally wound heating coil 15 of exposed microfine wire having one end secured by a screw 16 to the upper end of the receptacle and making electrical contact with the receptacle and the lower end fastened by a screw 17 to the head of a pin 18 which passes through the bottom of the receptacle and is suitably insulated therefrom by an inner and outer pair of fiber washers 19 and 20 and a fiber collar 21.

22 is a lock nut screw threaded on the end of the pin and holding the same tightly in position while 23 is an adjusting nut located on the outer end of the pin. Two contact washers 24 and 25 are inserted on the pin between the nuts.

The attachment is contained in a suitable electric circuit so that the coil 15 can be heated. This circuit comprises in the present instance a battery 26 or other source of electrical motive force, feed and return wires

27 and 28 and a switch 29, the feed wire being connected through the switch with the engine at any convenient point while the return wire is connected with the attachment by passing the end thereof between the washers 24 and 25 and screwing up the nut 23.

30 is an inverted saucer shaped hood contained in the well and located to overhang 10 the attachment, the object of this hood being to collect the oil vaporized by the attachment and pass it directly to the orifice 10 and subsequently to the mixing chamber. It will be seen that with this device 15 applied the oil from the well will fill the cup and that the oil filling the cup will be quickly vaporized once the circuit containing the coil is closed as the coil is directly in contact with the liquid. The oil so vaporized passes up in bubbles through the oil well and is trapped by the hood and fed directly to the mixing chamber through the orifice. As the capacity of the receptacle is comparatively small and the heating coil 25 is comparatively large it only takes a few seconds to vaporize the oil in the receptacle and consequently it is possible with this device to start the engine almost instantaneously even where an oil such as kerosene 30 or coal oil is used.

We do not wish to be restricted to the application of our invention to a carbureter as it will be readily understood the attachment could be applied on any engine feed 35 pipe for vaporizing purposes provided of course it is attached at a suitable point so that the oil vaporized by it can be immediately mixed with the air supply and passed to the cylinder.

40 What we claim as our invention is;

1. The combination with an engine carbureter having an oil well, mixing cham-

ber and communicating orifice, of a receptacle opening to the well and designed to be filled with oil from the well, means for heating the oil within the receptacle, and means coöperating with the receptacle for deflecting the vaporized oil toward the orifice. 45

2. The combination with an engine carbureter provided with the usual oil well, of 50 a receptacle opening to the well and designed to be filled with oil from the well and means for electrically heating the oil in the receptacle, as and for the purpose specified. 55

3. The combination with an engine carbureter provided with the usual oil well, of a cup shaped receptacle secured to the bottom of the well and opening to the interior thereof, an insulating casing within 60 the receptacle, an electrical heating coil within the casing and a suitable electric circuit containing the coil, as and for the purpose specified.

4. The combination with an engine carbureter provided with the usual oil well and outlet orifice, of a cup shaped receptacle 65 screw threaded into the bottom of the well and opening to the interior of the same, an insulating casing contained within the receptacle, an electrical coil mounted in the casing and contained within a suitable electric circuit and a collecting hood contained in the well above the inlet orifice and overhanging the receptacle, as and for the purpose specified. 70 75

Signed at Winnipeg this 11th day of February 1914.

ARNOLD WILLIAM MANSBRIDGE.
SIDNEY JOHN NASH.
